UNITED STATES PATENT OFFICE.

EDWARD DAVIS, OF CAMBRIDGE, MASSACHUSETTS, ASSIGNOR OF ONE-HALF
TO E. B. WELCH, OF SAME PLACE.

TELEPHONE.

SPECIFICATION forming part of Letters Patent No. 433,981, dated August 12, 1890.

Application filed November 19, 1885. Renewed February 14, 1887. Serial No. 227,604. (No model.)

To all whom it may concern:

Be it known that I, EDWARD DAVIS, of Cambridge, in the county of Middlesex and State of Massachusetts, have invented certain new and useful Improvements in Telephones, of which the following is a specification.

This invention has for its object, first, to reinforce the receiving instrument or telephone of a telephone-circuit, and thus increase the effect of its sound vibrations, and also provide a telephonic instrument capable of being used either in a circuit to re-enforce a receiving-telephone, and thus increase the sound sent over the line from a transmitting-instrument or a transmitting or receiving telephone, its principal use, however, being to reinforce a receiving-telephone.

To these ends my invention consists, first, in the combination, with the main line of a telephone-circuit, an induction-coil, the secondary of which is included therein, of a re-enforcing apparatus consisting of a polarized electro-magnet included in the main line, two diaphragms separated by a space containing powdered carbon or other variable resistance, one of said diaphragms being in close proximity to the electro-magnet, and a primary circuit comprising a battery, the primary of the induction-coil, and the two diaphragms, the arrangement being such that said re-enforcing apparatus intensifies or strengthens the sound transmitted over the line at the receiving-telephone, said apparatus being also capable of being used as an electric telephone for transmitting or receiving articulate sounds, all of which I will now proceed to describe and claim.

In the accompanying drawings, forming a part of this specification, Figure 1 represents an elevation of the case or holder supporting the polarized electro-magnet, the diaphragms, and carbon filling. Fig. 2 represents a section on line Y Z, Fig. 1. Fig. 3 represents an elevation of the opposite side of the casing from that shown in Fig. 1. Figs. 4, 5, and 6 are detached views of the diaphragms. Fig. 7 is a diagram of my improved circuit.

The same letters and figures of reference indicate the same parts in all the views. In the drawings, 1 represents the line-wire of a telephone-circuit having a transmitter

(not shown) and a receiving or hand telephone T.

L represents a polarized electro-magnet, and S an induction-coil located between the transmitting and receiving instruments, the line passing through said electro-magnet and through the secondary of the induction-coil.

G and F represent the two diaphragms supported by a case or holder, as hereinafter described, and separated by a space containing a filling H of powdered carbon or other variable resistance. Said diaphragms are included in a primary circuit composed of said diaphragms, the carbon filling H, a battery V, the primary of the induction-coil, and wires 2', and 2'', respectively, connecting the diaphragm G with one pole of the battery, the other pole of the battery with the primary of the induction-coil, and the diaphragm F with the primary of the induction-coil, said diaphragms being the electrodes or terminals of the primary circuit.

The sound-waves, passing through the line and through the electro-magnet and the secondary of the induction-coil, act on the diaphragm G and the primary circuit, of which said diaphragms form a part, to cause variations of the strength of the battery in said circuit, which act inductively to cause an undulating current in the secondary of the induction-coil. This undulating current is added to that sent forth by the induction-coil, and therefore re-enforces the receiving-telephone and greatly increases the effect of the sound-waves, making the speech much louder and clearer than that transmitted by any other apparatus of which I am aware, heretofore or now in use.

Referring to Figs. 1, 2, 3, 4, 5, and 6, A represents a ring of non-conducting material having an internal shoulder A', which serves to support and keep apart the diaphragms F G, the space between said plates containing the powdered carbon H. A circular plate of metal B, with a central perforation, as shown, is secured to one face of ring A by means of screws B', and between said plate and the diaphragm F is inserted a ring E, so that, on screwing down screws B', plate B and ring E will press diaphragm F against shoulder A', and thereby secure said diaphragm firmly in place, while,

by the insertion of ring E, a shallow chamber is formed between the plate B and diaphragm F, as is usual in magnetic telephones or receivers. The diaphragm G is held in place 5 against shoulder A' by means of screws I', and a ring I, pressed by said screws firmly against said plate, as shown in Fig. 2. The diaphragms F G are preferably provided on their inner sides with points or projections F' 10 G', preferably of platinum or other refractory conductor, the preferred arrangement of these points being shown in detail in Figs. 4, 5, and 6. As shown, in this case plate F is provided with one row of points F', while plate G has 15 two rows G', so that when said plates are in position in the telephone, as shown in Fig. 6, there will be three concentric rows of points, one row attached to plate F and two to plate G. The practical effect of this arrangement 20 is to increase the area of contact of the plates with the carbon placed between; also, to prevent the packing of the carbon. It is not necessary to adhere to precisely the described 25 form or arrangement of the points on said plates. The number and form of said points or projections may be greatly varied without departing from the principle involved. If desired, the points may be placed on but one of the diaphragms as when one diaphragm is 30 made of a very thin piece of platinum or other conducting metal.

The permanent magnet L, preferably of the curved form shown in Fig. 3, is secured to frame A, and has attached to one of its 35 poles the electro-magnet K, which is in close proximity to the diaphragm G, the magnet L, electro-magnet K, and diaphragm G being relatively arranged, as in a magnetic telephone.

40 Four binding-posts D D' D'' D''' secured to frame A, are connected one to each of diaphragms F G, and the other two to the terminals of electro-magnet K.

My invention is not limited to the described 45 details of construction, as the polarized magnet, the diaphragms, and the carbon filling may be supported by any other suitable means.

The instrument shown in Figs. 2 and 3 may 50 be used as a telephonic transmitter, and when so used is preferably provided with a trumpet-shaped mouth-piece C to concentrate the sounds of the speaker's voice and conduct them against the diaphragm F. When the 55 instrument is thus used, the variations of pressure on the carbon H, caused by the sound-waves impinging on the diaphragm F, cause variations of resistance, and therefore of current in the primary of the induction-coil S, 60 which variations act inductively to cause an undulating current in the secondary of said coil, and therefore in line 1, as with all carbon telephones or transmitters. At the same time the electro-magnetic effects produced by 65 the vibrations of diaphragms F G in close proximity to the pole of magnets L and K also produces an undulatory current, which

is added to that sent forth by the induction-coil S, as before described. It is also probable that as diaphragms F G and the contained 70 carbon H form a movable conductor carrying a current and moved into and out of a magnetic field by the action of the sound-waves that this may also add to the effect, according to well-known law. This would 75 add to the variation of the current in the primary of the induction-coil S, and therefore to the undulatory current in the line 1. The practical effect of this arrangement is to 80 produce a telephonic transmitter of great power, and transmitting speech much louder and clearer than the ordinary transmitter now in use. It is obvious that the direction of the current may be reversed and the diaphragms F G be used in a receiver instead of 85 a transmitter without departing from the spirit of my invention.

The entire apparatus described may be duplicated or multiplied, as may be desired, to increase the effect of the sound-vibrations 90 and adapt the apparatus to long-distance telephoning.

I am aware that powdered carbon confined by a diaphragm has been before used in connection with a telephonic transmitter. I am 95 also aware that a diaphragm vibrating in proximity to the poles of an electro-magnet for the purpose of transmitting articulate speech is not new.

I am aware of the constructions disclosed 100 by the United States Patent No. 272,329, granted February 13, 1883, to Rose and Cheever, of Patent No. 292,203, granted January 24, 1884, to Cheever, and of No. 231,239, granted August 17, 1880, to Rose; and I do not therefore claim, broadly, any feature disclosed in either of said patents.

I do not desire to claim herein the described method of increasing the current in the line to increase the amplitude of vibration in a telephone-receiver, as the same forms the subject-matter of another application filed January 8, 1887, Serial No. 223,746.

I claim—

1. In an electric telephone, the combination, 115 with a resistance material, such as powdered carbon, a diaphragm in contact with the same, an electro-magnet arranged in proximity to said diaphragm, so as to act upon it, an electric circuit containing a battery, the 120 resistance-varying material, and the primary of an induction-coil, of a main line, including the electro-magnet, the secondary of the induction-coil, and a telephone-receiver, said 125 electro-magnet diaphragm and resistance material being so arranged relatively that a current in the main line will produce a current of opposite polarity in the primary circuit of the induction-coil, as set forth.

2. In an electric telephone with a mass of 130 semi-conducting material, two conducting diaphragms confining said material, an electro-magnet arranged in proximity to one of the diaphragms, a circuit containing a bat-

tery, the semi-conducting material, and the primary of an induction-coil, of a main line, including the electro-magnet, the secondary of the induction-coil, and a telephone-receiver, the diaphragm opposite the one acted upon by the electro-magnet being arranged to receive and be acted upon by vibrations of the air, substantially as described.

In testimony whereof I have signed my name to this specification, in the presence of two subscribing witnesses, this 16th day of November, 1885.

EDWARD DAVIS.
